COMBINATION CLOCK AND RADIO-
RECEIVERHarry R. Van Deventer and Joseph A. Warren,
New York, N. Y., assignors to Patent Engineering
Corporation, a corporation of Delaware

Application April 7, 1932, Serial No. 603,791

18 Claims. (Cl. 250—14)

This invention relates to improvements in a combination clock and radio receiver, and has for its principal object the combination of a clock, preferably one with an electric driving

5 motor, and a radio receiving set in a single cabinet that is small and compact, the cabinet having the appearance of an ordinary mantel clock and being about 6½" wide, 6" deep and 10" high.

10 Another object of the invention is to produce a combination device of the type described in which a chassis carrying all of the parts of the radio receiving set except the loud speaker is readily removable from the cabinet without disassembly.

Another object is to provide a combination device of the class described in which the clock may be set from the front of the cabinet and is supported in the cabinet without being mounted on the radio chassis.

20 The invention consists substantially in the construction, combination, location and relative arrangement of parts, all as will be more fully hereinafter set forth as shown by the accompanying drawings and finally pointed out in the appended claims.

In the accompanying drawings:

Figure 1 is a front elevation of a combination clock and radio receiving set embodying the invention;

Figure 2 is a side elevation of the set, Figure 1;

Figure 3 is a side elevation, partly in section, of the set shown in Figures 1 and 2;

35 Figure 4 is a vertical sectional view of the set, Figures 1 and 2, with the front of the set removed in order to show the radio chassis and the loud speaker parts in place within the cabinet;

40 Figure 5 is a horizontal sectional view of the set on the line 5—5 of Figure 4;

Figure 6 is a horizontal sectional view of the set on the line 6—6, Figure 4;

Figure 7 is a front view of the radio receiver chassis removed from the set, Figure 1;

Figure 8 is a side view of the chassis, Figure 7; and

Figure 9 is a typical circuit which may be used in the combination clock and radio receiving set.

50 For the sake of illustration, the invention will be described as applied to a combination clock and radio receiver of the type above referred to, and although the invention will be disclosed herein and specific details of preferred embodiment

ments thereof disclosed, it must be understood that such details are not intended to be limitative of the invention except in so far as set forth in the accompanying claims.

The numeral 10 denotes a cabinet which may be made of wood or other suitable material. In the front of this cabinet is an opening 11 for the clock and an opening 12 for the dial and knobs of the radio receiver chassis. The cabinet also has two openings 13, 14 in the sides thereof to permit egress of sound from the loud speaker as hereinafter described. These openings may be covered by a cloth 15 to prevent the ingress of dirt and the cloth may be protected by a grille 16.

60 Secured to the front of the cabinet is a clock movement generally denoted by the numeral 17. This clock may be of any suitable type, either the ordinary hand wound spring driven type or as shown, a clock of the electric synchronous 65 type.

70 Secured to the front of the cabinet is a clock movement generally denoted by the numeral 17. This clock may be of any suitable type, either the ordinary hand wound spring driven type or as shown, a clock of the electric synchronous 75 type.

The clock movement is preferably mounted upon a face plate 18 which secures the same to the cabinet and attached to this face plate is the dial and the hinged sash 19 containing the usual glass crystal covering the dial and hands.

75 When an electric clock is used the motor is provided with a pair of extended flexible wires (not shown) for the purpose of connecting it in circuit as hereinafter referred to.

80 Secured to the bottom of the cabinet is the base 20 preferably of metal and sufficiently strong to withstand the bending action of a piezo-electric crystal 21 which is insulated 85 secured thereto by means of the bolts 22, 22.

85 The bolts 22, 22 pass through clamps 23, 23 secured to the sides of the crystals, said clamps having extending arms which are turned upwardly as shown at 24, 25 and which are attached in any suitable manner to the lower 90 edges 26, 27 of a diaphragm 28 which covers practically the entire side walls and top of the interior of the cabinet.

95 This diaphragm is preferably secured at 29 to the cabinet and when vibrated by the action 100 of the piezo-electric crystal in a known manner the sound produced finds egress through the openings 13, 14 in the cabinet.

A pair of flexible wires (not shown) are connected to the piezo-electric crystal or to the 105 bolts 22, 22 which are in circuit therewith and may be used to connect the crystal in circuit with the other parts of the radio set as herein-after described.

110 It will now be observed that the cabinet 10 is

equipped with a clock and with a loud speaker and that the driving mechanism for the loud speaker is so disposed within the cabinet that it does not occupy much room, and the diaphragm 5 of the loud speaker is so disposed that practically the entire space within the interior of the cabinet may be utilized for the other parts necessary in a radio receiving set.

The remaining parts that are necessary for 10 the radio receiving set are assembled upon a framework or chassis 30 which may be of aluminum or other suitable material and of any desired construction. It is preferably made from a flat stamping having the edges turned over 15 and spot welded.

The sides of the framework extend downwardly and are bent inwardly to form ears or lugs 31, 31, which engage the rails 32, 32 which are attached to the bottom framework of the cabinet. These rails are provided on their rearward ends with the spring latches 33, 33, and the pins connecting with these spring latches engage and hold the lugs and consequently the 20 entire chassis securely in place.

25 In order to remove the chassis, the spring latches 33, 33 are pushed upward thereby withdrawing the pins connected thereto from the holes in the ears 31, 31 as shown in Figure 3 and the entire chassis is pulled out of the cabinet 30 from the rear thereof.

The chassis comprises the framework carrying 35 all parts necessary for the radio receiver except the loud speaker. As any suitable circuit may be used and as different instrumentalities are necessary when different circuits are used the various instrumentalities to be mounted upon the chassis are not described in detail but by way of illustration a chassis is described in which the circuit and component parts are as 40 shown in Figures 7 to 9 inclusive, and include two 4 microfarad electrolytic filter condensers designated by the numerals 34, 34 which are bolted to the top wall 35 of the framework 30.

45 Mounted upon this top wall and secured there- to in any suitable manner is a suitable 2-gang tuning condenser 36, the projecting shaft carrying the movable plates of same being equipped with a pulley 37 to which is connected a flexible wire belt or other suitable member 38 which 50 is wrapped about and secured to the lower pulley 39 secured to a sleeve 40 supported upon a shaft 41 upon which it is free to turn. Rigidly secured to the sleeve 40 is the control knob 42 provided with the usual dial 43.

55 When the chassis is in place in the cabinet the dial 43 may be observed through the opening 44 in the plate 45 and by turning the knob 42 the tuning condenser may be adjusted in the usual manner.

60 The shaft 41 extends outwardly through the knob 42 and has upon its outer end a volume control knob 46 and secured to its inner end a suitable volume control shunt 47, supported on the intermediate wall 48 of the framework 30.

65 Between the horizontal walls 35 and 48 is suitably secured a support 49 of insulating material on which are mounted the usual flexible springs or other socket members, some of which are shown at 50, 50 for the vacuum tubes 70 51, 51. The tubes shown in the accompanying drawings are of a special type but it will be understood that any suitable type may be used. These tubes are provided with the usual insulating bases 52, 52 which pass through holes in 75 the top wall 35 and the usual projecting pin

terminals 53 extend through holes in the support 49 and engage the socket members 50, 50, the tubes being thereby rigidly supported in an operative position on the chassis.

The tuning coils 54, 54 are mounted in any 80 suitable manner in a pair of metallic shields 55, 55 which completely enclose the coils and which are mounted in any suitable manner in contact with the metallic framework 30. Wires connecting to these coils are brought out through holes in the shields so that they may be connected in circuit.

85 A power transformer 56 is mounted on a side wall 57 of the framework 30 and supplies filament current to the tubes 51, 51 it being understood that any suitable number of tubes may be employed depending upon the circuit used. The choke coil for the filter circuit is shown at 58 and is mounted on a side wall 59 of the framework. Grounding condenser 60 may be mounted upon the intermediate horizontal wall 48 as shown.

90 The output choke coil 61 is also mounted on the intermediate wall 48 as shown in Figure 4.

95 The foregoing constitute the main parts of the chassis assembly and there are a few additional parts used in connection with the circuit shown in Figure 9 which are mounted within or upon the complete chassis as shown in Figures 7 and 8, and these parts will be described in connection with the circuit shown in Figure 9. As the shape and location of these parts may vary within wide limits they have not been shown in connection with Figures 3 to 6 inclusive for the sake of clarity.

100 The complete chassis as just described is wired up as shown in Figure 9, a binding post 62 (not shown) being insulatedly mounted on the chassis for connection to the antenna. A binding post 63 is connected to the framework 30 and 105 constitutes a common ground for the ground side of all of the various circuits.

110 A switch indicated diagrammatically at 64 in Figure 9 forms part of the volume control shunt 47 and is operated by the knob 46. When 115 the knob is turned from the extreme left hand position clockwise it first closes the switch and then places more or less of a resistance 47 in circuit. As such combination switches and resistances are in common use they are not here described in detail.

120 The detector tube in this circuit is indicated at 65, and this together with the four amplifier tubes 51, are connected in circuit as shown, the plates and external grids of said tubes being 125 connected to the plate voltage feed 66 of the transformer circuit through suitable resistances 67.

130 A high resistance 68 connects from the plate voltage feed to the ground. A mercury vapor rectifier tube 69 is provided in circuit with the windings of the transformer 56, the usual 110 volt alternating current supply being connected to the binding posts 70 insulatedly supported at any suitable place on the chassis. When an electric clock is used, the driving motor of same is connected directly across the binding posts 70 as shown at 17, Figure 9, so that the clock will not be disconnected when the switch 64 is 140 operated.

145 A pair of insulatedly supported binding posts 71, 71 are provided to which the wires from the loud speaker herebefore referred to are connected when the chassis is in place, the piezo- 150

electric loud speaker being designated by the number 72 in Figure 9.

A small lamp 73 is mounted on the intermediate wall 48 and is connected across the filament supply circuit as shown. When the radio set is turned on, the light from this lamp shines through an aperture in the front wall 74 of the framework 30 and shines through the translucent dial 43 which is carried on the knob 42 and the dial may be observed through the opening 44 in the plate 45. Suitable connections 75, 75 (not shown) are provided on the chassis in order that when the same is in place the wires from the clock motor 17 (Figure 9) may be connected thereto.

In operation the chassis shown in Figure 7 carrying all of the parts of the radio set except the loud speaker is pushed into place in the cabinet as previously described and when in place occupies the position in respect to the loud speaker and clock as shown in Figures 3 and 4, the connections being made between the speaker and its binding posts 71 and between the binding posts 75, 75 for the connections to the clock, antenna 62 and ground 63. Connections being made and the terminals 70 connected to a suitable source of alternating current supply, the clock will immediately proceed to operate and by opening the hinged sash 19 the clock hands may be set without removing the chassis from the cabinet.

By operating the projecting knobs 42 and 46, the radio set may be turned on and the tuning condensers operated and the volume of the set regulated.

While the radio set is in operation the lamp 73 will be lit. When the radio set is not in operation this lamp will be extinguished as it is controlled by the switch 64.

If it is desired to remove the radio chassis from the cabinet the same may be removed as heretofore described.

The cabinet may be provided with a removable back (not shown) and is preferably provided with rubber cushioned feet.

If desired, the detector tube 65 and any of the amplifiers 51 may be shielded by means of the metallic shields 76 secured to the top wall 26 of the framework.

What is claimed is:

1. A radio receiver including a cabinet, a framework removably supported in said cabinet and containing radio detecting, amplifying and tuning means, a diaphragm surrounding the side walls of said framework, and means comprising a speaker driving mechanism for vibrating said diaphragm mounted on said cabinet subjacent said framework.

2. A radio receiver including a cabinet having a base portion, a framework adapted to support parts of the radio receiver including radio detecting, amplifying and tuning means removably supported in said cabinet above the base portion thereof, a diaphragm within said cabinet having an edge extending downwardly toward the base thereof, and means comprising a speaker driving mechanism for vibrating said diaphragm mounted in the base portion of said cabinet below said framework.

3. A radio receiver including a cabinet having a bottom portion, a framework removably supported in said cabinet above the bottom thereof and containing radio detecting, amplifying and tuning means, a diaphragm having an edge extending downwardly toward the bottom of said

cabinet, means for vibrating said diaphragm secured to said downwardly extending edge, and a rigid metallic plate supporting said means and secured to the bottom of said cabinet below said framework.

80

4. A radio receiver including a cabinet containing radio detecting, amplifying and tuning means, a rigid plate secured therein and forming the bottom closure thereof, a piezo-electric crystal secured to said plate, and a diaphragm located in said cabinet above said plate, secured to said crystal and adapted to be vibrated thereby.

85

5. A radio receiver including a cabinet having openings in its sides and containing radio detecting, amplifying and tuning means, a plate closing the bottom of said cabinet, a piezo-electric crystal secured to said plate, and a diaphragm secured to said crystal and adapted to be vibrated thereby said diaphragm extending around the inner side walls of the cabinet and having free vibratory portions adjacent the openings therein.

90

6. A radio receiver including a cabinet, and containing radio detecting, amplifying and tuning means, a base member adapted to close the bottom of said cabinet, a piezo-electric crystal secured to said member, a diaphragm within the cabinet having its surface in extended relation to the inner side walls and top thereof, and means for detachably securing said diaphragm to said crystal.

100

7. A radio receiver including a cabinet having a rounded top and containing radio detecting, amplifying and tuning means, a base member secured to said cabinet, a piezo-electric crystal secured to said base member, a diaphragm within said cabinet secured to said crystal and extending along the sides and across the top of the cabinet, and means for securing said diaphragm to the inner wall of the cabinet at a point intermediate its ends.

110

8. A radio receiver including a cabinet, a piezo-electric crystal mounted in said cabinet, a diaphragm connected to said crystal in said cabinet in extended relation to the side walls and top thereof and covering practically all of the area of said side walls and top and defining an open space within the cabinet, a framework adapted to support parts of said radio set removably positioned within said space within the cabinet, a tuning condenser and a volume control mounted on said framework, and control means including knobs connected to said condenser and volume control extending from the front of said cabinet.

115

9. A radio receiver including a cabinet having a front wall, a framework having a top wall and removably supported in said cabinet, a variable condenser having a shaft and mounted upon said top wall, a sleeve mounted in said framework and extending from the front thereof and through the front wall of said cabinet, means connecting said sleeve and shaft whereby the latter may be moved by rotating the former, a shaft in said sleeve extending outside said framework and cabinet, and a combination volume control and switch carried on said framework connected to said last shaft and movable therewith.

125

10. A radio receiver including a cabinet, a framework removably supported in said cabinet, a variable condenser having a shaft supported on top of said framework, a control shaft supported in the lower portion of said framework,

150

- 4
1. A sleeve surrounding said shaft, a connection between said sleeve and the shaft of said condenser, a volume control connected to said control shaft and supported in said framework, and knobs mounted upon said sleeve and shaft located outside said cabinet whereby the control of said radio receiver may be effected.
2. A radio receiver including a cabinet, a framework removably supported therein said framework having substantially closed sides, front and top, and being open in the back and bottom, a variable condenser mounted on the top of said framework, a support of insulating material within the framework and below openings therein, socket members secured to said support, a plurality of vacuum tubes mounted in said socket members through the openings in said framework, volume control means mounted on said framework below said condenser, and means for adjusting said volume control means and said condensers extending from said framework and through the wall of said cabinet.
3. A radio receiver including a cabinet, a clock mechanism mounted in the front thereof, a hinged sash mounted on the front of said cabinet and adapted to cover the dial and hands of said clock, a shaft having a sleeve rotatable thereon extending from the face of said cabinet below said clock knobs secured to said sleeve and shaft, a tuning condenser and a control device connected to said sleeve and shaft and movable therewith, a framework upon which said control device, condenser, sleeve, shaft and knobs are supported, said framework being removable as a unit from the cabinet without disturbing said clock and connections in said cabinet whereby said clock and radio receiver may be operated from a single current source.
4. In a radio receiver a removable chassis comprising a framework having an apertured top wall, filter condensers mounted on said wall, variable tuning condensers comprising a framework carrying fixed and movable plates and a shaft mounted upon said wall, vacuum tubes in the apertures in said wall, a support of insulating material having socket members thereon positioned below the apertures in said wall and adapted to receive the terminals of said tubes, metallic shields for said tubes mounted upon said wall, a cabinet adapted to contain said chassis and a speaker having a diaphragm secured to said cabinet and surrounding the top and sides of said chassis.
5. In a radio receiver a chassis comprising a framework having a top wall, a variable condenser mounted thereon having a shaft, a plurality of tuning coils mounted below said top wall, said coils having shields secured to said wall, a volume control member secured to said chassis below said tuning coils, means for regulating said volume control extending from the front of said chassis, means supported by said volume control means and connected to the shaft of said variable condenser and extending outside said chassis whereby the capacity of said condenser may be manually varied, a plurality of vacuum tubes mounted upon said chassis, a transformer mounted within the chassis and a cabinet having means engaging projecting lugs on said chassis whereby the chassis containing
- all of the aforementioned parts may be removably locked in position within the cabinet.
6. A combination clock and radio receiver comprising a cabinet having openings in each side and the front thereof, an electric clock secured in the front opening of said cabinet, a loud speaker diaphragm adjacent the side openings in said cabinet, means for actuating said diaphragm mounted in the bottom of said cabinet leaving a clear space in the interior thereof, a removable chassis adapted to carry upon its walls radio receiver parts to operate said means, said chassis being positioned in the clear space in the interior of said cabinet, control means mounted upon said chassis and extending through the front of said cabinet and a circuit including a source of current connected to said chassis and adapted to furnish current to said radio receiver parts and to said electric clock mechanism.
7. A combination clock and radio receiver comprising an outer cabinet, an electric clock secured to the front wall of said cabinet in the upper portion thereof, a loud speaker having its actuating mechanism secured to the bottom of said cabinet and its diaphragm adjacent the side walls thereof, a removable chassis adapted to carry upon its walls radio receiver parts including a variable condenser positioned on the upper part of said chassis, said condenser having a shaft substantially parallel to said clock shaft, control means for said condenser including a shaft extending through the wall of said cabinet, volume control means for said loud speaker mounted upon said chassis and including means extending through the front of said cabinet for operating said control means and a circuit including a source of current connected to said chassis and adapted to furnish current to said radio receiver parts and to said electric clock.
8. A combination clock and radio receiver comprising a cabinet, an electric clock secured to a wall of said cabinet, a loud speaker having its actuating means mounted in the bottom of said cabinet and its diaphragm adjacent the inner side walls thereof, a removable chassis adapted to carry upon its walls radio receiver parts to operate said speaker actuating means, a volume control for said speaker mounted upon said chassis, a variable condenser mounted upon said chassis, a switch associated with said volume control means, means including concentric shafts connected to said condenser and volume control means and extending outwardly through a wall of said cabinet, a graduated dial connected to the shaft associated with said condenser, a lamp mounted on said chassis adapted to illuminate said dial and a circuit including a source of current connected to said chassis and adapted to furnish current to said radio receiver parts, said lamp and said clock.
